COMBINATION VALVE AND AIR CHARGER

Jack E. Piccardo, Oakland, Calif., assignor, by
mesne assignments, to Barnes-Shasta Pump
Co., a corporation of California

Application September 8, 1947, Serial No. 772,827

1 Claim. (Cl. 103—6)

1

The invention relates to automatic flow valves and air chargers of the type disclosed in my Patent No. 2,416,345 dated February 25, 1947, and more particularly to an improved form of air charger for incorporation in such a device.

An object of the present invention is to provide in a combination valve and air charger of the character described an improved form of air charger in which diaphragms and equivalent devices heretofore used are eliminated and a structure provided utilizing a simplified type of piston and cylinder arrangement and wherein the piston clearance within the cylinder is so determined and so cooperates with the other related parts as to avoid the use of one set of check valves customarily required in this type of mechanism.

A further object of the invention is to provide an air charger of the type described having a water lubricated, full floating, water packed, piston moving entirely within a surrounding fluid bath to substantially completely eliminate wear and deterioration of the moving parts.

A further object of the invention is to provide an air charger of the character described which is composed of a minimum number of sturdily formed parts which are designed for maximum simplicity in manufacture and assembly and which are composed of material affording a substantially unlimited period of useful life.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claim.

Referring to said drawings:

Figure 1 is a somewhat pictorial view of a pump and connected well and storage tank parts with a portion of the pump shown in cross-section to illustrate the functioning of the several parts.

Figure 2 is a cross sectional view of a valve and air charger shown in Figure 1 and constructed in accordance with the present invention.

Figure 3 is a cross sectional view taken substantially on the plane of line 3—3 of Figure 2.

The valve and air charger of the present invention is designed for incorporation in a water pump and pressure storage system as illustrated in Figure 1. Such a system incorporates a centrifugal pump 7 usually mounted adjacent the head of a well and operatively connected by

means of a discharge pipe 8 to a valve unit 9, incorporating the air pump and pressure tank charger of the present invention. The latter is here shown connected by a conduit 11 to a pressure tank 12. A suction pipe 13 extends from the intake of the centrifugal pump to below the level of the water source and for pump installation wherein the water level is below the effective direct-lift capacity of the centrifugal pump a water elevation system as, for example, an ejector 14, is incorporated in the pump intake for providing an augmented and accelerated fluid lift. In this latter case a conduit 16 is tapped into the pump at the discharge side thereof for conducting water under pressure in a reverse direction to the flow of intake 13 to the ejector 14. The ejector unit 14 is well known in the art and is described in my previous patent aforesaid and in brief includes a nozzle and venturi combination for elevating the well water in the pipe 13 to within the operating range of the pump 7. A foot check valve 17 is preferably provided below the ejector unit 14 for admitting water to the pump and to automatically close upon discontinuance of pump operation to prevent draining of the water from the pump and maintaining the pump prime. The function of the valve and air charger unit 9, as described in my patent aforesaid, is to maintain a requisite back pressure within the discharge chamber of the pump so as to force water under pressure down through conduit 16 to the ejector unit 14, and secondly to introduce into the water discharge into tank 12 a charge of air which forms a head or cushion at the top of tank 12 to maintain a prolonged pressure within the tank as water is withdrawn therefrom. Usually an air pressure of from 20 to 40 pounds per square inch is desirably maintained within the tank. As water is withdrawn from the tank and the air pressure head expanded accordingly with an attendant drop of pressure, the pump is automatically placed in operation when the pressure within the tank is lowered to the minimum desired level, say 20 pounds per square inch. This is accomplished by a pressure responsive electric switch 18 which is connected to the tank, in the present case by conduit 20 to the unit 9, and which automatically functions to open and close the electric circuit energizing the electric motor 19 connected to the pump, as the pressure within the tank reaches its upper and lower limits, 40 and 20 pounds per square inch respectively.

Unit 9, containing the air pump and fluid flow valve mechanism of the present invention, is

incorporated in a generally cylindrical housing 21 having a cap portion 22 for closing an open end thereof. An intermediate wall 23 is provided in the housing, dividing the interior into inlet and discharge chambers 24 and 26, respectively; chamber 24 being defined by wall 23 and cap 22 and communicating with the centrifugal pump by means of the pipe 8; and chamber 26 being defined by housing end wall 27 and wall 23 and communicating with the water storage tank by means of pipe 11. Wall 23 is provided with a bore or aperture 28 connecting chambers 24 and 26 and is aligned with a hollow longitudinal extension 29 extending from the end wall 27 which defines a cylinder 31 in communication with the outlet chamber 26. Thus a continuous fluid circuit is established, including the centrifugal pump, conduit 8 communicating with inlet chamber 24, thence to the outlet chamber 26 via aperture 28, and to the pressure storage tank by means of discharge conduit 11. As a means of insuring a requisite back pressure at the pump discharge in order to actuate the ejector unit 14, as above described, a valve is appropriately interposed in the aperture 28 so as to selectively restrict the flow of water from the pump to the storage tank in the above described circuit. In accordance with the present invention such a valve comprises a hollow piston 32 slideably mounted for reciprocation in the aperture 28 and being formed with valve ports or side wall openings 33 which, when positioned in opposed position to wall 23 permit the passage of water through the aperture 28. Also, in accordance with the present construction the piston 32 is mounted for reciprocation within the cylinder 31 and in its fully extended position, as shown in Figure 2, the closed end 34 of the piston is moved into a substantially closed position against the closed end 36 of the cylinder. It will thus be seen that the piston is at all times fully supported and properly guided in its reciprocation, not only in the aperture 28 but also in the axially aligned cylinder 31, and that the degree of opening and closing of the valve, depending upon the degree of registration of ports 33 with wall 23, is a function of the longitudinal displacement of the piston.

In accordance with the present construction, the relative longitudinal positioning of the piston and the corresponding amount of restriction of water flow through the valve is controlled in proportion to the discharge pressure of the pump. Where, for example, the outlet of the tank is opened for continuous flow and therefore the pump 7 is pumping against practically no back pressure, the piston valve is automatically moved to restrict the flow sufficient to produce a requisite back pressure to energize the ejector unit 14 as above described. On the other hand, when the tank discharge is closed and the back pressure on the pump is thus built up, the piston valve is correspondingly opened so as to minimize the restriction of the flow to the tank. This pressure responsive drive means for the piston valve here comprises a diaphragm 37 formed of rubber neoprene or other relatively impermeable and flexible material and secured between appropriate flanges 38 and 39 formed on the opposed ends of housing 21 and cap 22, the flanges here being clamped together by means of a plurality of screws 41. The diaphragm is secured to the closed end 42 of the piston extending into chamber 24 such as here shown by opposing reinforcing plates 43 and 44 and a screw 46. As

will be seen from Figure 2, the diaphragm 37 is positioned in the inlet chamber substantially mid-way between wall 23 and the end wall 47 of cap 22, and provides in addition to the chamber 24 (defined between the diaphragm 37 and the wall 23) a second fluid tight chamber 48 defined between the diaphragm 37 and the end wall 47. The chamber 48 is connected by conduit 49 to the suction intake 51 (see Figure 1) of the pump so that the pressure differential generated by the pump in operation is applied across the diaphragm 37 normally displacing the diaphragm to the right, as seen in Figure 2, diminishing the size of chamber 48 and correspondingly increasing the size of chamber 24. This movement of diaphragm is resiliently resisted by a helical spring 52 which is mounted in chamber 48, with the opposite ends of the spring supported on the end wall 47 of the chamber and the diaphragm reinforcing plate 44. When the pump is not in operation the spring 52 normally positions the piston in its extended position as illustrated in Figure 2, wherein the aperture 28 is completely closed by the piston. On starting of the pump, the diaphragm 37 is moved rapidly to the right as viewed in Figure 2 and displaces the piston 32 to register the ports therein with the wall 23. Depending then on the pressure in chamber 24, due to the load pressure on the pump, the diaphragm, piston valve and helical spring 52 will reach a position of equilibrium, that is a position where the valve restriction creates a back pressure which balances the spring compression. As the pressure in the storage tank builds up, so will the pressure in chamber 24 and the diaphragm will be moved further to the right, thus opening the valve towards its full open position. On the other hand, a drop in load pressure will be accomplished by movement of the diaphragm to the left, as viewed in Figure 2, thus choking the water flow and creating a higher back pressure in chamber 24 to maintain the ejector 14 in operation, as above described. Preferably a set screw 53 is provided in the end wall 47 of the closure 22 and which contacts the head of screw 46 to limit the opening movement of the valve. The set screw 53 may thus be set at the maximum valve opening, which still affords the minimum back pressure to operate the ejector 14, depending upon the particular well conditions. Desirably the set screw 53 projects into a recess 54 provided in the exterior side of the end wall 47 and after appropriate adjustment of the screw 53, the recess may be closed by a threaded closure plug 56 to prevent unauthorized tampering of the adjustment.

The air pump function and pressure tank air charger of the present invention is incorporated in the selective flow control hereinbefore described as an integral and functionally cooperative part thereof. It is desirable to discharge a quantity of air into the fluid storage tank upon each cycle of operation of the pump so as to insure the maintenance of the air cushion within the tank, and desirably and as here shown the addition of such air is accomplished without the necessity of a conduit separate from the water inlet 11 for admitting air to the storage tank.

In the present construction utilization is made of the reciprocating piston 32 and cylinder 31 for affording an air pump construction. As will be seen from Figure 2, a one-way air check valve 57, sometimes referred to as a snifter valve, is mounted in the end wall 36 of the cylinder so as

to admit air from the atmosphere into the cylinder opposite the head end 34 of the piston. A Schraeder type tire valve is suitable for this purpose and is here shown mounted in a conventional inner-tube valve chuck threaded into the head end 36 of the cylinder. On starting of pump operation and displacement of the piston to the right, as illustrated in Figure 2, the air chamber 58 defined between the head end 34 of the piston and the end 36 of the cylinder, is enlarged and air is drawn in through the check valve 57 to take up the piston displacement. On discontinuance of pump operation and displacement of the piston to the left, as viewed in Figure 2, under the operation of spring 52, valve 57 automatically closes and the air entrapped in the aforesaid chamber 58 is forced around the sides of the piston—through the clearance between the piston sidewalls and the cylinder—into the water discharge chamber 26 where the air is entrained in the water passing to the tank on subsequent operation. As an important feature of the present invention I have found that by selectively controlling the clearance between piston 32 and its cylinder 31 the use of a customary second check valve to prevent the flow of water into the air chamber 58 may be obviated. This is possible in the present construction due to the rapidity of movement of the piston and corresponding rapid enlargement of chamber 58 on starting of pump operation, and the relatively greater viscosity of water as compared to air. In other words, during the displacement of the piston to enlarge the air chamber, air will enter the chamber through a relatively small aperture in the valve 57 in greater quantity than water will enter the same chamber through the clearance between the piston and the cylinder even though a considerable clearance is provided. Thus a clearance is selected which inhibits but does not prevent the passage of water. Water which does pass through this clearance and into the air chamber is forced back into the discharged chamber 26 upon movement of the piston to its closed position. The amount of water which passes through this clearance is not important so long as a requisite amount of air is drawn into the air chamber during displacement of the piston. I have found that this clearance range is from one-thousandth (0.001) of an inch to six thousandth (0.006) of an inch. If the clearance is less than 0.001" difficulty is encountered in passing the air through this clearance on movement of the piston to its closed position. On the other hand, if the clearance is greater than 0.006", the water flow past the piston is not impeded sufficiently to draw in a requisite amount of air. Thus I have provided in the present structure a piston which is at all times surrounded by and is supported in full floating relationship in a film or body of water thereby providing automatic lubrication and sealing of the piston and minimizing the wear and deterioration of the several parts. Preferably the piston and the cylinder are formed of a

non-oxidizing and non-corrosive material such as bronze so as to have a substantially unlimited life and insure the maintenance of the requisite clearance as above described.

If desired, a pressure gauge 59 may be attached to the unit 9 to indicate the discharge pressure and desirably the gauge is threaded into an opening 61 provided in the top side of the body 21 in registration with chamber 24. The removal of gauge 59 provides a ready means, through opening 61, to prime the pump. Preferably in order to get all of the air out of the system during the priming operation, a removable plug 62 is provided in an opening 63 in the end wall 47 at the top of chamber 48. Thus in priming, water may be introduced through opening 61, which in turn fills the pump and conduits 13 and 16 down to the closed foot valve 17 and until water backs up through conduit 49 and is discharged through the opening 63. When the system is thus filled with water the plug 62 and the pressure gauge 59 are inserted in their respective openings.

I claim:

In an air charger of the character described, a casing having an interior wall defining on opposite sides thereof water inlet and discharge chambers, a cylinder communicating with said discharge chamber and having a closed distal end, a piston slidably mounted in an opening in said wall and mounted for reciprocation in said cylinder, said cylinder having an internal diameter greater than the outside diameter of said piston whereby there is provided a predetermined clearance between the sides of said piston and the sides of said cylinder, a pressure responsive drive means provided in said inlet chamber and connected to said piston to effect reciprocation thereof in said cylinder and relative to said wall, said piston being formed with a peripheral valve port at a position on the length of said piston movable to and through said opening upon said reciprocation of said piston and functioning to control the water flow through said opening in accordance with the pressure of said inlet chamber, and an air inlet check valve mounted in said closed cylinder end for admitting air into said cylinder upon displacement of said piston away from said end, said clearance being within the range of 0.001 to 0.006 of an inch and functioning as a check valve impeding the flow of water around said piston and providing the sole means for permitting the flow of said admitted air into the water flowing through said valve port.

JACK E. PICCARDO.
